By his Attorney
Edgar V. Hale, Esq.

UNITED STATES PATENT OFFICE.

HILLARY C. LONG, OF NEW YORK, N. Y.

SKATE DEVICE.

1,380,914.

Specification of Letters Patent. Patented June 7, 1921.

Application filed May 8, 1920. Serial No. 373,740.

To all whom it may concern:

Be it known that I, HILLARY C. LONG, a citizen of the United States, and residing at New York, in the county of New York 5 and State of New York, have invented certain new and useful Improvements in Skate Devices, of which the following is a specification, such as will enable those skilled in the art to which it appertains to make and 10 use the same.

This invention relates to skate devices of approximately the same general form as a roller skate which is designed particularly for use by theatrical folks, and especially acrobats and is adapted for use 15 upon the head of the user, and the object of the invention is to provide a device of the class and for the purpose specified which is simple in construction and operation, 20 strong and durable, and which is constructed as hereinafter described and claimed.

The invention is fully disclosed in the following specification, of which the accompanying drawing forms a part, in which 25 the separate parts of my improvement are designated by suitable reference characters in each of the views, and in which:—

Figure 1 is a diagrammatic view illustrating one method of using the skate device 30 in performing a novel acrobatic feat;

Fig. 2 a side view of my improved skate device with part of the construction broken away;

Fig. 3 a bottom plan view of the construction shown in Fig. 2 with part of the construction broken away and with parts in section;

Fig. 4 a plan view of the construction shown in Fig. 2 with parts of the construction broken away;

Fig. 5 a partial section on the line 5—5 of Fig. 4;

Fig. 6 a partial section on the line 6—6 of Fig. 5; and,

Fig. 7 a view similar to Fig. 2 but showing only a part of the construction on a reduced scale and showing a modification.

In Fig. 1 of the drawing I have shown for the purpose of illustrating one use of my 50 invention, a performing apparatus 10 comprising an inclined runway 11, a cross section of which is shown in Fig. 6 of the drawing, and the top face of the runway 11 is cut out at the corner portions thereof 55 to form grooves 12 in which channel irons 13 are mounted, and said channel irons form

a track or runway for the skate device as hereinafter described. The runway 11 is supported in position by a suitable framework, part of which is indicated at 14 in 60 Fig. 1 of the drawing, and it will be noted that the lower end portion of the runway 11 is curved upwardly as shown at 15, and in the use of the device an acrobat passing downwardly over the runway with one of 65 my improved skate devices 16 upon his head will pass through the air in an arc approximately similar to that indicated at 17 and will land upon a suitably supported platform 18.

The skate device 16, in the form of construction shown, consists of a frame member 19 comprising a top plate 20 having downwardly directed side flanges 21 enlarged at their lower ends as shown at 22 75 to form bearings for shafts 23 and 24 mounted in the front and rear end portions of the frame member 19. The shafts 23 and 24 extend beyond the outer face of the flanges 21 and wheels or rollers 25 are rotatably mounted on the extensions of the shaft 23 and smaller rollers 26 are rotatably mounted on the extensions of the shaft 24. The shafts 23 and 24 are locked against 80 rotation in the frame member by set screws 26 and 27, as clearly shown in Fig. 3.

The top plate of the frame member 19 is provided with a large central aperture 28, which is approximately elliptical in form, as clearly shown in Fig. 3, and secured to 90 the upper face of the plate 20 is an elliptical sheet metal ring 29, which serves to secure a flexible fibrous hood member 30 to the frame member 19, said hood member being located between the ring 29 and the top 95 plate of the frame member 19, as clearly shown in Figs. 5 and 6, and the central top portion 31 of the hood is adapted to close the aperture 28 in the top plate 20.

Secured to the ring 29 is an annular 100 cushion ring 32 known in the profession as a "drumette" and which is preferably composed of a center core 33 of twisted rope wrapped with tape 34, and then inclosed in a casing 35 of felt or similar padding material. The ring 32 is secured to the ring 29 by wire loops or other similar means 36, as indicated in Fig. 6 of the drawing. The hood member 30 is shaped to conform with the head of the user and to closely fit the 105 same and is provided at intervals with extending straps 37 which facilitate the proper

placement of the hood on the head. The skate device is firmly held in engagement with the head by a heavy elastic strap or band 38, one end portion of which is secured to a loop 39 permanently secured to one of the side flanges 21 of the frame member 19 and the other end of the strap 38 is provided with a hook-shaped device 40 which is adapted to be placed beneath the other side flange 21, as clearly shown in Figs. 2, 3 and 6 of the drawing, after the strap has been passed beneath the chin of the user as is diagrammatically illustrated in Fig. 1 of the drawing.

15 In the use of the skate device, the same is placed upon the head of the acrobat or performer with the large wheels or rollers 25 at the front portion of the head, or above the forehead, and the acrobat or performer stands upon his head at the top of the runway 11 and places the wheels or rollers 25 and 26 in the angle iron tracks 13 as shown in Fig. 6, and descends down over the runway in a balanced position and leaps the gap between the lower end of the runway and the platform 18 and lights upon the platform on his head or the skate device thereon as is diagrammatically illustrated in Fig. 1. The inner faces of the wheels or rollers 26 are beveled inwardly to a slight extent as shown at 41 to provide for a free action of said wheels or rollers on the tracks or runways 13, and to prevent binding or unnecessary friction which would cause the acrobat or performer to lose his balance, and it will be understood that the wheels or rollers 25 and 26 will be properly hardened to withstand the strain and to give long and durable service.

40 It will also be apparent that by providing large wheels or rollers 25 at the front of the skate device and smaller wheels or rollers 26 at the rear end thereof, the performer will be able to obtain a proper balance while descending on the runway 11 or will keep his head in the proper relative position with his body. The same result may be accomplished, however, by providing two wheels or rollers 42 of the same size which are mounted in connection with a frame member 43 similar in all respects to the frame member 10 but which is inclined upwardly and forwardly as is clearly shown in Fig. 7 of the drawing.

55 My skate device is not necessarily limited to the use herein shown and described, or in connection with a runway and in performing a leap the gap acrobatic feat, but may be used in any desired manner, or in various performances, and while I have shown and described certain details of construction for carrying my invention into effect, I am not necessarily limited to these details, and various changes therein and modifications thereof may be made, within the scope of the

appended claims, without departing from the spirit of my invention or sacrificing its advantages.

Having fully described my invention, what I claim as new and desire to secure by Letters Patent, is:—

1. A device of the class described comprising a suitable frame member, two pairs of anti-friction rollers rotatably mounted in connection with the frame member, and means whereby said frame member is adapted to be connected with the head of a user. 75

2. A skate device of the class described comprising a suitable frame, rotatable members mounted in connection with said frame, and a hood member on said frame and by means of which said skate device may be secured upon the head of the user. 80

3. A device of the class described comprising a suitable frame, two pairs of anti-friction members mounted in connection with said frame, a hood member on said frame, and a cushion ring secured to said frame within said hood member. 85

4. A device of the class described comprising a suitable frame, two pairs of anti-friction members mounted in connection with said frame, a hood member on said frame, a cushion ring secured to said frame within said hood member, and a flexible strap 95 mounted in connection with said frame.

5. A device of the class described comprising a suitable frame, two pairs of anti-friction members mounted in connection with said frame, a hood member on said frame, a cushion ring secured to said frame within said hood member, and a flexible strap mounted in connection with said frame, one end portion of said strap being permanently secured to the frame and the other end portion thereof detachably connected therewith. 100

6. In a device of the class described, a frame comprising a top plate having side flanges, shafts mounted in the end portions of said flanges, wheels rotatably mounted on said shafts, and a hood member secured to the top plate of said frame. 110

7. In a device of the class described, a frame comprising a top plate having side flanges, shafts mounted in the end portions of said flanges, wheels rotatably mounted on said shafts, a hood member, a metallic ring for securing said hood member to the top plate of the frame, and an annular cushion member mounted within said hood member and secured to said metallic ring. 115

8. In a device of the class described, a frame comprising a top plate having side flanges, shafts mounted in the end portions of said flanges, wheels rotatably mounted on said shafts, a hood member, the top plate of said frame being provided with an aperture, a metallic ring secured to said top plate about the aperture therein and adapted to secure said hood to said frame, an annular 125

cushion member secured to said metallic ring, and an elastic band mounted in connection with one of the side flanges of the frame and adapted to be detachably connected with the other side flange thereof. 5

9. In a device of the class described, a frame comprising a top plate having flanges at the opposite sides thereof, shafts mounted in the end portions of said flanges and 10 extending therethrough, wheels rotatably mounted on the extensions of said shafts, the wheels on one of said shafts being larger than those on the other shaft, and the inner faces of said wheels being beveled inwardly 15 toward the axis thereof.

10. In a device of the class described, a frame comprising a top plate having flanges at the opposite sides thereof, shafts mounted in the end portions of said flanges and 20 extending therethrough, wheels rotatably mounted on the extensions of said shafts, the wheels on one of said shafts being larger than those on the other shaft, and the inner

faces of said wheels being beveled inwardly 25 toward the axis thereof, a cushion member mounted in connection with the top plate of said frame, and an elastic band one end of which is secured to one of the flanges of said frame and adapted to be detachably connected with the other flange thereof. 30

11. A performing apparatus of the class described comprising a skate device consisting of a suitable frame, wheels mounted in connection with said frame, a hood secured to said frame, an inclined runway over which 35 said skate device is adapted to pass, and means on said runway for guiding the wheels of said skate device in its movement thereon.

In testimony that I claim the foregoing as my invention I have signed my name in presence of the subscribing witnesses this 7th day of May, 1920.

HILLARY C. LONG.
